UNITED STATES PATENT OFFICE.

FREDERICK GEORGE CREED, OF CROYDON, ENGLAND.

MULTIPLE-HULL BOAT.

1,422,542.

Specification of Letters Patent. Patented July 11, 1922.

Application filed December 3, 1919. Serial No. 342,226.

(GRANTED UNDER THE PROVISIONS OF THE ACT OF MARCH 3, 1921, 41 STAT. L. 1813.)

To all whom it may concern:

Be it known that I, FREDERICK GEORGE CREED, a subject of the King of Great Britain and Ireland, residing at Croydon, 5 in the county of Surrey, England, have invented Improvements in or Relating to Multiple-Hull Boats (for which I have filed application in Great Britain November 25, 1918, Patent No. 150,004), of which the following is a specification.

This invention has for its object to provide a boat or ship (hereinafter called a ship) having greater stability, manœuvring qualities and safety from sinking or shipwreck, greater facility for loading and unloading, greater comfort for passengers and many other advantages over boats or ships as heretofore usually constructed and hereinafter referred to for comparison as standard craft.

For this purpose, a ship according to the present invention comprises a deck, frame or super-structure suitably supported upon and rigidly or flexibly connected to three 15 or more floats so disposed as to the centre of gravity of the ship as to give the maximum stability in all directions when afloat.

The floats or buoyant bodies (hereinafter called floats) which support the superstructure, may be made of any convenient shape or size to enable them to pass easily through the water. One or more of the floats may be arranged in such a way that it or each of them can be turned about a 20 more or less vertical axis for steering purposes and about a more or less horizontal axis for trimming the ship, that is to say, for determining the float line, or for checking rolling or pitching, or for each of these 25 purposes. Or one or more rudders and one or more inclinable planes may be attached to one or more of the floats, or to the superstructure, and act upon the water for like 30 purposes, each float being rigidly connected to the superstructure. Or one or more of the floats may be adapted to be turned about a vertical axis or axes for steering purposes and be provided with one or more inclinable planes for trimming the ship. The floats 35 may be of more or less cylindrical or equivalent shape with tapered or rounded ends and are hollow, and contain air or other fluid lighter than water.

Motion may be imparted to the ship by

means of one or more screw or other propellers acting on the water and mounted for example in or on one or more of the floats and driven in any known or suitable manner. Or the ship may be driven by air propellers, or by gases or other fluids 40 acting upon the water, or by sails, or by oars, or by two or more or all of these means. In some cases the boat may be so small as to serve as a toy.

The superstructure may carry the various 45 cabins, holds, and other offices of a ship for accommodating passengers, crew, cargo, fuel, engines and so forth. Some of these 50 may be accommodated in one or more of the floats. The superstructure may be built 55 high enough above the water to allow the highest waves to pass freely underneath. It is suitably connected to the floats, as by 60 means of stream line framework or supports so as to offer minimum resistance to 65 the waves. For facilitating access to the floats, or to one or some of them, from the superstructure, some portion or portions of 70 the connecting framework or supports may be made hollow. The floats may for safety 75 be divided into or adapted to form any desired number of water-tight compartments.

In the accompanying illustrative drawings, Fig. 1 is a side elevation and Fig. 2 80 an underside view, showing diagrammatically, one construction of ship according to the invention. Figs. 3 and 4 are vertical sections at right angles to one another, showing, to a larger scale than Figs. 1 and 2, 85 means for rotating one of the floats about 90 a vertical axis and for inclining it about a horizontal axis. Figs. 5 and 6 and also Figs. 7 and 8, are similar views to Figs. 1 and 2 respectively, showing modified arrangements. Fig. 9 shows partly in side 95 elevation and partly in vertical section, a further modified arrangement.

In the arrangement shown in Figs. 1 and 2, *a* is the superstructure of the ship supported by pillars *b*, *b*¹, *b*² from three floats *c*, *c*¹, *c*², one of the floats, namely *c*, being arranged in the rear of the other two, namely *c*¹, *c*², which are arranged abreast. The float *c* with its pillar *b* is arranged with its vertical axis in a longitudinal vertical plane 100 passing midway between the vertical planes containing the vertical axes of the other two floats *c*¹, *c*² with their pillars *b*¹, *b*², so

that the superstructure is supported at three places arranged triangular-wise the floats being so disposed in relation to the centre of gravity of the ship as to give the maximum stability to the ship in all directions when afloat. The superstructure *a* may be of any desired construction to suit the purpose for which the ship is to be used, and carry various cabins, holds or other offices as and for the purposes hereinbefore mentioned. The floats *c*, *c*¹, *c*² are made of circular section with tapered end portions to facilitate easy passage through the water and of sufficient size and buoyancy to support the superstructure, each of them being subdivided, as hereinbefore mentioned, to form a number of water-tight compartments. The pillars *b*, *b*¹, *b*² are made of oval or equivalent section, also to facilitate easy passage through the water, when immersed therein, and are made hollow so that access can be gained through them to the interiors of the floats. In the example now being described each of the two front floats *c*¹, *c*² is made of larger size and therefore of greater buoyancy than the rear float *c* and they are rigidly connected through their pillars *b*¹, *b*², to the superstructure *a*. They are provided with propellers *d* driven by motors, conveniently electric motors, located in them and driven from a power plant *a*¹ arranged on the superstructure *a* at a part thereof above and between them.

The rear float *c* is capable of being turned about a vertical axis for steering purposes and about a horizontal axis for trimming the ship. For these purposes, the hollow pillar *b* in the example shown in Figs. 3 and 4, is rigidly connected at its lower end to the float *c*. At its upper end it is provided with lateral flange-like extensions *f* of circular shape having an axis at *g* in the float and which are arranged to work in corresponding guide-ways *h* formed by curved guide plates *h*¹. These guide-plates are fixed to a rotary head or turntable *i* mounted to rotate in a horizontal circular guideway formed by a guide ring *k* fixed to the lower part of the superstructure *a*. The junction between the pillar and rotary head and between the head and the lower part of the superstructure, are made watertight and antifriction devices are or may be arranged between the relatively movable parts to facilitate easy movement of such parts. Fixed to the turntable *i* is a circular rack *m* with which gears a pinion *n* driven by an electric or other motor *o* carried by the lower part of the superstructure. To the rotary head *i* is fixed the upper end of a vertical structure *p* the lower end of which is adapted to serve as a bearing *r* for a shaft *s* fixed transversely within and to the float *c*. Fixed to one side of and within the upper part of the pillar *b* is a plate or bracket *t* that extends

above the rotary head *i* and is provided with a segment *u* of a worm wheel. With this segment gears a worm *v* the spindle of which is mounted in bearings *w* on the rotary head and is arranged to be driven by an electric or other motor *x* mounted on the rotary head. As will be seen, the arrangement is such that the float *c* can be turned about a vertical axis for steering purposes by operating the motor *o* and turning the rotary head *i*, and pillar *b*, and the said float can be turned about the horizontal axis *g* of the shaft *s*, as indicated by dotted lines in Fig. 3, by operating the motor *x* in one or other direction and moving the upper end of the pillar *b* in the curved guideways *h* by the worm gear *u*, *v*. The pillar *b* may be provided at opposite sides with two worm wheel segments each operated by a worm as described, *y* is a housing for the motors and associated parts.

The pillars *b*, *b*¹ and *b*² can be made of any desired height. The pillars *b*¹, *b*² may be connected together and to the superstructure *a* by any suitable arrangement of framework, preferably of stream line shape.

In the modified arrangement shown in Figs. 5 and 6, the pillar *b* with its float *c* is rigidly connected to the superstructure *a* and each of the pillars *b*¹, *b*² with its float *c*¹, *c*² is connected to the superstructure in the manner hereinbefore described with reference to Figs. 3 and 4 so that each of such floats can be turned about a vertical axis and also about a horizontal axis. In this example the rear float *c* is made of greater size and buoyancy than the front floats *c*¹, *c*² which serve as balancing floats, and the power plant *a*¹ is arranged on the superstructure *a* so as to be above the float *c*.

In the modified arrangement shown in Figs. 7 and 8, each of the pillars *b*, *b*¹ and *b*² with its float *c*, *c*¹ or *c*², is rigidly connected to the superstructure *a*, and the float *c* is provided at its lower side with a rudder 1 mounted to turn about a vertical axis for steering purposes, and at its opposite sides with fins or blades 2 arranged to be turned about a horizontal axis at 3, for trimming the ship. The rudder and fins or blades are adapted to be operated from the superstructure by any convenient arrangement of mechanism extending downward through the pillar *b*. In this case, the three floats may be made of equal size and buoyancy, the float *c* being the leading float and the floats *c*¹, *c*² propelling floats.

The adjustable float, or each adjustable float, may, as shown in Fig. 5, be provided with vertical fins 4.

According to a further modification, the float *c* with its pillar *b* may be mounted to turn about a vertical axis for steering purposes and be provided with inclinable planes worked by mechanism extending downward 130

through the pillar for trimming the ship. Such an arrangement is shown diagrammatically in Fig. 9 wherein the float C, adapted to be rotated about a vertical axis as hereinbefore described, is provided on each of its opposite sides with an inclinable plane 2 fixed to a horizontal shaft 3 capable of being turned in bearings 4 in the float by a lever arm 5. This arm extends upward through the pillar b and is provided with a toothed segment 6 capable of being turned about the axis of the shaft 3 by a worm 7 rotated by a reversible electric motor 8 so as to vary the inclination of the planes 2.

15 As will be obvious, the supporting means between the superstructure a and the floats c, c¹, c² can be of other construction than that shown, which however are simple and effective. Also, more than three floats can be used 20 if desired.

In some cases, the floats when in their normal positions may be immersed well below the surface of the water where there is little or no disturbance from waves. By this 25 means greater stability will be obtained. In such a construction each float may have attached to it or the framework or supports above it, and connecting it to the superstructure, an auxiliary float disposed at or near 30 the surface of the water so as to act as a stabilizer to prevent or minimize tilting, rocking or rolling motion. When the supporting means between the floats and superstructure is in the form of hollow pillars as described, such pillars will, when partly immersed, serve also as auxiliary floats for the 35 purpose mentioned.

The floats however large, may be made detachable and replaceable, as by using flanged 40 and riveted joints between them and the pillars or equivalent, and by using larger or smaller floats, which may be of different shapes, the carrying capacity of the ship and its speed can be varied. Also, one or some of 45 the floats may be hermetically sealed so as not to be in communication with the corresponding hollow pillar or pillars.

A ship constructed as described has many 50 advantages. For example, stability and consequent freedom from sickness and strain for passengers, crew and livestock, and freedom from or lessened stress on engines, mountings and framework of engines, boilers, cargo and other parts. It cannot be upset and is very 55 difficult to sink. It can be manœuvred more easily than standard craft and can turn in its own length or nearly so. Engines and mounting can be lighter, owing to their not being subject to rolling and pitching. No 60 ballast is required. Perishable cargo can be carried more safely, and speed should compare well with standard craft.

Also, such a ship can be designed for use 65 as a war ship, for which purpose it would possess many important practical advan-

tages, including that of providing a steady platform for guns and difficulty of sinking it by collision, torpedoes or the like, particularly when the floats are sub-divided to form a number of separate water-tight compartments.

The superstructure can be more conveniently arranged for all purposes than in the case of standard craft, and for passengers it is much superior, as all can have fresh 75 air and room for exercise with entire absence of the nauseating smells common to standard craft. The ship can be docked, loaded and unloaded more easily than standard craft owing to its more convenient construction 80 and ease of manœuvre.

It is to be understood that the various parts of a ship constructed as hereinbefore described are shown only diagrammatically in the drawings and will, in practice, be 85 specially designed to suit the end in view.

What I claim is:—

1. A ship embodying a superstructure and a plurality of float-structures each embodying a float, one of said floats being horizontally rotatable for steering purposes and having a hollow supporting member, means for rotating the float through the medium of said hollow supporting member, said rotatable float carrying trimming means consisting of a pair of vanes arranged at opposite sides of the float, a transverse shaft carrying said vanes, and means for rocking said shaft embodying a member extending up through the tubular member and rotatable with the 100 float.

2. A ship embodying a superstructure and a plurality of float structures each embodying a float, one of said floats having a hollow supporting member, vanes arranged at opposite sides of said float, a transverse shaft carrying such vanes and extending through the float and means for rocking said shaft and vanes comprising a member extending up through said tubular member and motor 105 mechanism above said tubular member for rocking said upwardly extending member, shaft and vanes.

3. A ship embodying a superstructure, a plurality of float-structures for supporting 115 the same on the water, one of said float-structures being horizontally rotatable for steering purposes and having a hollow rotatable supporting member, vanes arranged at opposite sides of said float-structure, a transverse shaft extending through said float-structure and carrying said vanes, and means for rocking said shaft to tilt said vanes in either direction embodying a member extending up through the tubular member and a motor mechanism for rocking said 120 upwardly extending member, shaft, vanes and motor mechanism being rotatable with the tubular member and float-structure.

4. A ship embodying a superstructure and a plurality of float-structures each embodying a float, one of said floats having a hollow vertical supporting member adapted to turn about a vertical axis for rotating said float horizontally for steering purposes, bearing means between the super-structure and the upper end of said tubular member, toothed gearing between said super-structure and tubular member for rotating the latter, a transverse shaft extending through said float, vanes arranged at opposite sides of said float and fixed to the ends of said shaft, a member extending up through the tubular member and connected to said shaft and motor mechanism carried by the upper end of said tubular member and adapted to rock said upwardly extending member, shaft and vanes.
- 10 5. A ship embodying a super-structure, three floats each carrying a supporting member for such super-structure, two of said floats being arranged abreast of each other and at a distance apart transversely and the third float being arranged centrally with but at a distance from the other two in the longitudinal direction, one of said floats having a tubular supporting member, vanes arranged at opposite sides of said float, a transverse shaft extending through said float and carrying said vanes and means for rocking said shaft and vanes embodying a member extending up through said tubular member and motor mechanism for rock-35 ing said upwardly extending member.
6. A ship embodying a super-structure, three floats each having a tubular supporting member connected to said super-structure, two of said floats being arranged abreast of each other and at a distance apart transversely and the third float being arranged centrally with but at a distance from the other two in the longitudinal direction and horizontally rotatable with its tubular sup-40 porting member for steering purposes, means for rotating said horizontally rotatable float and its supporting member, vanes arranged at the opposite sides of said third float, a transverse shaft extending

through such float and carrying said vanes, 50 and means for rocking said shaft and vanes embodying a member extending up through the associated tubular supporting member, and rocking mechanism therefor above said supporting member.

7. A ship embodying a superstructure, a plurality of floats, connecting members supporting said superstructure above said floats and above the surface of the water in which the floats are to move, one of said connecting members being tubular, vanes arranged at opposite sides of the float connected to said tubular member and mounted to turn about transverse horizontal axes, rocking means arranged within said float and connected through the sides thereof to said vanes, whereby the latter can be moved simultaneously from a horizontal position either into an inclined forward and downward position or into an inclined rearward and downward position, and means extending upward through said hollow member for operating said rocking means.

8. A ship embodying a superstructure, a plurality of floats, tubular connecting members for supporting said superstructure above said floats and above the surface of the water in which said floats are to move, vanes mounted at opposite sides of said floats to turn about transverse horizontal axes, rocking means arranged within each float and connected through the sides thereof to the corresponding vanes and adapted to move the vanes simultaneously from a horizontal position into either a forward and downward position or into a rearward and downward position and operating means extending upward through each tubular connecting member and connected to the rocking means for the vanes of the corresponding float, whereby said floats can be caused to descend or ascend to the surrounding water or to move in a horizontal direction therein at will.

Signed at London, England this 10th day 95 of November, 1919.

FREDERICK GEORGE CREED.
